DESIGN FOR A LADY'S HAT

Isidor Kaplan, New York, N. Y.

Application April 30, 1934, Serial No. 51,585

Term of patent 3½ years

To all whom it may concern:

Be it known that I, ISIDOR KAPLAN, a citizen of the United States, residing at the Borough of Manhattan, in the city, county, and State of New York, have invented a new, original and ornamental Design for a Lady's Hat, of which the following is a specification, reference being had to the accompanying drawing forming part thereof.

Fig. 1 is a perspective view of a lady's hat embodying my new design.

Fig. 2 is a side elevation of the same.

Fig. 3 is a top plan view of the same.

The characteristic feature of the design resides in the lines of the crown running from the front toward the rear thereof, giving a tailor-made effect.

I claim:

The ornamental design for a lady's hat as shown and described.

ISIDOR KAPLAN.
